UNITED STATES PATENT OFFICE.

JOSEPH DELANCY, OF BUCYRUS, OHIO, ASSIGNOR OF ONE-HALF TO
F. A. WISE, OF BUCYRUS, OHIO.

WRENCH.

SPECIFICATION forming part of Letters Patent No. 787,359, dated April 18, 1905.

Application filed September 10, 1904. Serial No. 223,934.

To all whom it may concern:

Be it known that I, JOSEPH DELANCY, a citizen of the United States, residing at Bucyrus, in the county of Crawford and State of Ohio, have invented a new and useful Wrench, of which the following is a specification.

This invention relates to that class of wrenches employed for operating upon round objects, such as pipes.

10 The object is to provide a novel and simple structure of this character that has a powerful gripping action, will operate in a confined space, and is not only reversible, but may be provided with interchangeable parts, so that 15 its range of usefulness can be greatly enlarged.

The preferred embodiment of the invention is illustrated in the accompanying drawings, wherein—

20 Figure 1 is a side elevation of the wrench. Fig. 2 is a longitudinal sectional view therethrough. Fig. 3 is a cross-sectional view on the line 3 3 of Fig. 1. Fig. 4 is a similar view on the line 4 4 of Fig. 1.

25 Similar reference-numerals indicate corresponding parts in all the figures of the drawings.

In the embodiment illustrated a stock 5 is employed, one end of which is adapted to form 30 a handle, the other end being enlarged into a jaw-head 6, that tapers toward its free end, said tapering sides being serrated or toothed and one being straight, while the other is curved. The head is bifurcated, and slots 7, 35 located longitudinally in the opposite sides of the stock, extend to the bifurcation. Associated with the head is a swinging jaw 8, having a right-angular extension in the form of a shank 9, located in the bifurcation of the 40 head and secured therein by means of a pivot-screw 10. The jaw has its inner face serrated, as shown at 11, and the shank is likewise provided with a toothed face 12. A leaf-spring 13 is secured to the shank 9 by suitable means— 45 as, for instance, a screw 14—said spring being arranged to extend longitudinally into either of the slots and being held in place by a keeper-pin 15, that bridges the slot and is secured to the stock. The walls of both slots are pro-

vided with openings 16 for the reception of 50 the keeper-pin.

In using this device the jaw 8 is swung backwardly sufficiently to permit the introduction of a pipe or other article between the same and the rear face of the stock-head. This swinging movement bends the spring 13, and therefore puts tension thereon, so that when the jaw is again released it is swung backwardly and into engagement with the article. The stock is then turned in the usual manner or 60 is held, the article being gripped between the opposing jaw-faces. This structure has a powerful gripping action and, furthermore, a pipe located close to the floor or in a similar confined space can be engaged and operated therewith. 65 The wrench can be readily reversed by removing the swinging jaw, turning the same, and again securing it by the pivot-pin. In this case the spring is located in the opposite slot and is held in place by the keeper-pin 15, 70 which is also changed, as will be evident. The wrench may furthermore be given a particularly great range or field of action by supplying therewith jaws of different sizes, which can be substituted for that shown. The purpose of placing the spring in the groove is to get 75 it out of the way, where it will not pinch the hand and will not break off or become deranged when the wrench is thrown down.

From the foregoing it is thought that the 80 construction, operation, and many advantages of the herein-described invention will be apparent to those skilled in the art without further description, and it will be understood that various changes in the size, shape, proportion, and minor details of construction 85 may be resorted to without departing from the spirit or sacrificing any of the advantages of the invention.

Having thus described my invention, what 90 I claim as new, and desire to secure by Letters Patent, is—

1. In a wrench, the combination with a stock, of a swinging jaw pivoted to the stock at one end, a leaf-spring secured to the jaw 95 and slidably extending longitudinally along one side of the stock, and a keeper extending transversely of the stock and across an inter-

mediate portion of the spring, said spring having such intermediate portion slidably bearing against the keeper.

2. In a wrench, the combination with a stock having a tapered bifurcated head provided with serrated faces, said stock also having longitudinally-disposed slots in its opposite sides, which slots extend to the bifurcation, a swinging jaw having a stem located and pivoted in the bifurcation of the head, said jaw being reversible, a leaf-spring secured to the stem and adapted to be arranged in either of the slots, and a detachable keeper-pin for bridging the slots over the spring.
- 15 3. In a pipe-wrench, the stock shaped at one end to form a handle and having its other end enlarged into a jaw-head, which is tapered

toward its free end, one tapering side being serrated or toothed and extending in a straight line, while the other tapering side is curved and slightly offset, said jaw-head being bifurcated, in combination with a swinging jaw having a right-angular extension pivoted in the bifurcation, and a leaf-spring carried by the jaw and having a slid able engagement with the stock.

In testimony that I claim the foregoing as my own I have hereto affixed my signature in the presence of two witnesses.

JOSEPH DELANCY.
